UNITED STATES PATENT OFFICE

103,103

DESIGN FOR AN AUTOMOBILE TIRE

Harry C. Hower, Chicago, Ill.

Application November 9, 1936, Serial No. 65,786

Term of patent 7 years

To all whom it may concern:

Be it known that I, Harry C. Hower, a citizen of the United States, residing at Chicago, in the county of Cook and State of Illinois, have invented a new, original, and ornamental Design for an Automobile Tire, of which the following is a specification, reference being had to the accompanying drawing, forming a part thereof.

In the drawing:

Figure 1 is a perspective view, partially in dotted lines, of a tire embodying the present design and taken from one side; and

Figure 2 is a fragmentary perspective view of the tire taken from the opposite side.

I claim:

The ornamental design for an automobile tire, as shown.

HARRY C. HOWER.
